(57) **CLAIM**

We claim the ornamental design for a head light for vehicle, as shown and described.

DESCRIPTION

FIG. 1 is a perspective view of head light for vehicle showing my new design;

FIG. 2 is a front elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a right side elevational view thereof; and,

FIG. 8 is a perspective view of the headlight with the transparent cover shown removed for clarity of illustration.
